CONE-TYPE CRUSHERS WITH SHOCK PAD BETWEEN FRAME AND ADJUSTMENT RING
Ivo D. Cook, Hurley, N. Mex., assignor to Kennecott Copper Corporation, New York, N.Y., a corporation of New York

Filed Dec. 17, 1964, Ser. No. 419,143
5 Claims. (Cl. 241—290)

ABSTRACT OF THE DISCLOSURE

A flexible and resilient shock pad of natural rubber or the like is interposed and compressed between mating rims of the frame and adjustment ring of a conventional cone-type gyratory crusher as a support for the ring, thereby maintaining the rim of the ring in substantially non-pressure relationship with the rim of the frame and practically eliminating wear and the need for adjustment.

Summary of invention

This invention relates to cone-type crushers as extensively used for intermediate crushing operations applied to ores and other rock materials.

This type of crusher is known generally as a "Symons" and operates on a gyratory principle. A cone-shaped head, covered by a hardened steel mantle, is mounted for gyratory movement within and relative to a stationary bowl, which has a hardened steel liner. The bowl is provided exteriorly with large and coarse threads, which mate with corresponding threads internally of an adjustment ring and enable the bowl to be turned during operation of the crusher for adjusting the setting with respect to the head to thereby control the gap between head and bowl.

The adjustment ring rests on a receiving rim of a stationary frame, and is normally held down tightly against such rim by bolts, which pass through coiled, tensioning springs. The bolts are adjusted so that the springs are tensioned sufficiently to hold the adjustment ring against the rim of the frame during normal crusher loads. However, under excessive loads and the presence of tramp iron or the like, the springs undergo compression and the adjustment ring and bowl are free to rise with the head and relieve excessive stresses and strains.

Due to this freedom of movement of the adjustment ring relative to its supporting seat on the main frame of the machine, wear occurs between the mutually engaging surfaces. Periodic rotation of the adjustment ring relative to the frame is required to even out the wear. This is not an easy job on such a large and heavy machine, and necessitates interruption of the continuity of operation of a mill where a sequence of operations are dependent upon continuing operation of one or more crushers.

A principal object of the present invention is to eliminate wear between the adjustment ring and the stationary frame, whereby the need for rotating the adjustment ring on its seat and the periodic work stoppages occasioned thereby are eliminated.

This object is effectively accomplished in accordance with the invention by modifying the ring and frame of such a crusher to accommodate therebetween a flexible and resilient shock pad of readily compressible material, such as natural rubber, for resiliently supporting the adjustment ring. It has been found that the interposing of such a shock pad between ring and frame eliminates wear, without interfering with proper action of the crusher.

There is shown in the accompanying drawings a specific embodiment of the invention representing what is

2

presently regarded as the best mode of carrying it out in practice. From the detailed description of this presently preferred form, other specific objects and features of the invention will become apparent.

5 In the drawings:

FIG. 1 represents a top plan view of a standard Nordberg-Symons cone crusher modified to incorporate the unique features of the invention;

10 FIG. 2, a fragmentary vertical section taken on the line 2—2 of FIG. 1;

FIG. 3, a horizontal section taken on the line 3—3 of FIG. 2;

15 FIG. 4, a fragmentary vertical section taken on the line 4—4 of FIG. 3 and drawn to a larger scale;

FIG. 5, a similar fragmentary section taken on the line 5—5 of FIG. 3; and

20 FIG. 6, a view corresponding to the significant portion of FIG. 2, so far as the invention is concerned, but showing the prior art, i.e. convention, construction for comparison with the inventive construction of FIG. 2.

Referring to the drawings:

The illustrated cone-type crusher is a standard Nordberg-Symons, manufactured by Nordberg Manufacturing Company, Milwaukee, Wis., which has been modified in accordance with the invention.

25 As is customary, the illustrated machine includes a cone-shaped head 10 covered by a hardened steel mantle 10a and mounted for gyration in conventional manner within a stationary bowl 11 having a hardened steel liner 11a internally thereof. The bowl 11 is threaded into an adjustment ring 12 by means of large and coarse threads 13.

30 Adjustment ring 12 rests on a stationary, structural frame 14 for upwardly yielding movement away from such frame when loading of material to be crushed between head and bowl is excessive or when the feed contains uncrushable foreign material, such as tramp iron. Tensioned coil springs 15 and bolts 16 provide for yieldability in conventional manner by means of a ratchet mechanism and windlass post 17, FIGS. 1 and 2, operable to rotate adjustment ring 12 on its threads 13 for purposes of adjustment.

35 As conventionally constructed, see FIG. 6, the stationary frame and the adjustment ring have sets of mated, bevelled surfaces 18 and 19, respectively, normally maintained in contact, but free to move relative to each other by reason of the aforesaid yieldable mounting of the adjustment ring on the stationary frame. The adjustment ring normally rests on the stationary frame, with the weight bearing directly on surfaces 18 through the overlying surfaces 19. This is the thing that causes difficulty in practice due to excessive wear between such mated surfaces 18 and 19, which necessitates removal and rotation of the ring to a new setting, usually 180° 40 from the old setting.

45 In accordance with the invention, existing machines are modified and new machines are constructed to include shock pad means between mutually spaced and opposed surfaces of adjustment ring and stationary frame, so the mated surfaces 18 and 19 will be held slightly apart, see the exaggerated showing of this in FIG. 2.

50 Thus, in the form illustrated, a flange extension 20, FIGS. 2—5, is provided peripherally of the upper rim 21 of the stationary frame 14, and a mating flange extension 55 22 is provided peripherally of the normal flange portion 23 of adjustment ring 12. These flange extensions are spaced apart sufficiently to receive a compressible shock ring 24, FIG. 2, of flexible, resilient, natural-rubber-like material therebetween. A shock ring made of 65-70 durometer, live, natural rubber and $\frac{3}{4}$ of an inch in thickness, put under compression of $\frac{3}{32}$ of an inch by tighten-

ing the bolts 16 so the conventionally-contacting sets of mated surfaces 18 and 19, FIG. 2, are spaced ever so slightly apart has been found to prevent wear between adjustment ring and stationary frame over very long periods of entirely satisfactory crushing surface rendered by the machine. The mated surfaces 18 and 19 can even be practically in face-to-face relationship, considering the fact that the compressed shock pad rather than the surfaces 18 bears the weight of the adjustment ring and that there is substantially no pressure relationship between the surfaces 18 and 19.

The resiliency and compressibility of the shock ring are important. When a ring made of 65-70 durometer, Buna-N, synthetic rubber was tried, there was not a sufficient degree of compressibility and too great spacing between the sets of mated surfaces 18 and 19 resulted. This led to a slight but undesirable wobble of the adjustment ring when extremely hard ore was being crushed. Thus, the shock ring should have compressibility equivalent to live natural rubber, and good judgment based on the type of ore to be crushed must be exercised in the tightening of the bolts 16.

Existing crushers can be modified in different ways to conform to this invention. Thus, the entire upper part of the conventional stationary frame can be cut off just below the reinforcing gusset plates normally provided, and an entirely new section welded on. The new section is preferably cast to proper formation with the extension flange 20. Lifting hooks 26 and gusset plates 27 are then welded thereto. Again, the worn portions of the conventional stationary frame can be built up by the use of welding techniques and machining, and a flange extension, lifting hooks, and additional gusset plates welded on.

In either case, the opposing surfaces of the flange extensions should be machined smooth for best results.

Newer forms of the stationary frame of a Nordberg-Symons cone crusher are provided with an outwardly extending flange of sufficient projection to make it unnecessary to make any modification prior to replacing the conventional adjustment ring with the modified ring of the invention. For these newer machines, it will be unnecessary to do more than modify the adjustment ring, by the addition thereto of a mating flange as previously described, and apply the modified ring to the existing stationary frame with a shock ring 24 interposed between the flanges of adjustment ring and frame.

Although it is preferred to make the mating or mutually confronting flanges continuous peripherally of both frame and adjusting ring and to provide the shock pad as a ring, such flanges can be made discontinuous, as projecting lugs, so long as they are symmetrically placed peripherally of frame and ring. As such, individual shock pads would be provided therefor.

Whereas there is here illustrated and specifically de-

scribed a certain preferred construction presently regarded as the best mode of carrying out the invention, it should be understood that various changes can be made and other constructions adopted without departing from the inventive subject matter particularly pointed out and claimed herebelow.

I claim:

1. In a cone-type crusher which includes a stationary frame having an upper rim, an adjustment ring having a lower rim mated with the said rim of the stationary frame, a bowl mounted within the adjustment ring, a cone-shaped head mounted for gyration within and relative to said bowl, and resilient means normally holding said ring and said frame together with their mated rims in mutually confronting relationship, shock pad means of flexible, resilient, natural-rubber-like material interposed and compressed between said frame and said ring so as to support said ring and maintain said mated rims in substantially non-pressure relationship.

2. The structural combination recited in claim 1, wherein the shock pad means is a ring.

3. In a cone-type crusher which includes a stationary frame having an upper rim, an adjustment ring having a lower rim mated with the said rim of the stationary frame, a bowl mounted within the adjustment ring, a cone-shaped head mounted for gyration within and relative to said bowl, and resilient means normally holding said ring and said frame together with their mated rims in mutually confronting relationship, peripheral flanges rigidly secured to and extending outwardly from the said rims, respectively, in mutually confronting relationship; and shock pad means of flexible, resilient, natural-rubber-like material interposed and compressed between the peripheral flanges of said frame and said ring so as to support said ring and maintain said mated rims in substantially non-pressure relationship.

4. The structural combination recited in claim 3, wherein the flanges are continuous peripherally of the frame and adjustment ring, respectively, and the shock pad means is a ring.

5. The structural combination recited in claim 3, wherein the flanges have flat and smooth confronting faces which are substantially normal to the vertical axis of the crusher and the shock ring has conforming flat and smooth faces at the opposite faces thereof.
